United States Patent Office

Des. 193,246
Patented July 17, 1962

193,246

FLOWER POT

Dirk Laan, Spoorsingel 38, Bovenkarspel, Netherlands

Filed Sept. 5, 1961, Ser. No. 66,599

Term of patent 14 years

(Cl. D35—3)

FIG. 1—1

FIG. 3—3

FIG. 1 is a side elevational view of a flower pot showing my new design;

FIG. 2 is a top plan view thereof; and

FIG. 3 is a vertical sectional view thereof, taken on line 3—3 of FIG. 2.

I claim:

The ornamental design for a flower pot, as shown and described.
